GREASE SHIELD FOR SKILLETS

Harry H. Willits, Louisville, Ky.

Application August 12, 1949, Serial No. 169,905

1. Claim. (Cl. 220—85)

2

I This invention relates to grease shields, and more particularly to a shield mountable on an ordinary skillet to prevent grease from spattering from the skillet onto objects and surfaces adjacent the skillet or onto a person using the skillet.

It is among the objects of the invention to provide an improved grease shield of simplified, one-piece construction which can be easily and economically manufactured from readily available sheet material, such as Duralumin or stainless steel, and will extend at least half-way around a skillet and from the rim of the skillet to a location substantially above the center thereof, which is easily adjustable to fit skillets of several different sizes, which fits entirely within the skillet so that grease cannot drip from the shield to the outside of the skillet, and which is mountable on the skillet by merely placing it thereon, yet will not accidentally fall off of the skillet during use.

Other objects and advantages will become apparent from a consideration of the following description and the appended claim in conjunction with the accompanying drawing, wherein:

Figure 1 is a side elevation of a skillet with a grease shield illustrative of the invention operatively mounted thereon;

Figure 2 is a top plan view of the skillet and grease shield illustrated in Figure 1; and

Figure 3 is a cross-sectional view of a fragmentary portion of the skillet and grease shield on the line 3—3 of Figure 2.

With continued reference to the drawing, the numeral 10 generally designates a skillet of ordinary construction, and the numeral 11 generally designates the grease shield of the invention shown operatively mounted on the skillet 10.

The skillet 10 has an annular side wall 12, and a bottom wall 13, and the edge of the side wall opposite the bottom wall constitutes a rim which may or may not have a bead or flange 14 formed thereon. A handle 15 is secured at one end to the side wall 12 of the skillet and projects radially therefrom.

As explained above, the skillet 10 is of well-known construction and constitutes no part of the present invention, except in the combination thereof with the improved grease shield.

The grease shield 11 is a body of thin sheet metal, such as Duralumin or stainless steel, having at least a moderate degree of resiliency, and is arcuately-curved in one direction on a radius approximately the same as the radius of curvature of the rim of the skillet on which the shield is to be used to include an angular interval of ap-

proximately 180-degrees. This body has a substantially straight top edge 16, and has an outwardly-deflected wing, as indicated at 17 and 18, at each end thereof. The bottom edge 19 of the shield is arcuately curved and inclined toward the top edge 16 from the mid-length location of the bottom edge toward each of the wings 17 and 18, so that when the shield is operatively positioned on a skillet, as illustrated in Figures 1 and 2, it will incline inwardly and upwardly from the rim of the skillet.

Two tabs 20 and 21 of U-shaped cross-section extend outwardly from the bottom edge 19 of the shield body at spaced-apart locations substantially symmetrically disposed relative to the mid-length location of the bottom edge of the shield to receive the rim of the skillet. Each of these tabs is elongated longitudinally of the bottom edge 19 of the shield and has its bight portion positioned somewhat above the bottom edge 19, so that when a skillet rim is received in the tabs, the bottom edge of the shield will be disposed within the skillet and somewhat below the skillet rim, so that any grease dripping from the shield will drip back into the skillet, and not outside of the skillet.

The material of the shield is preferably slotted, as indicated at 22, at the inner side of each tab, and at each end of each tab, so that the tabs are connected to the body of the shield by integral metallic necks of reduced width, and the tabs can thus be bent to the proper position to receive the rim of the particular skillet on which the shield is used. The two wings 17 and 18 are preferably given a slight concavity at their bottom ends, as indicated at 23, so that the bottom ends of these wings will engage the skillet rim and assist in maintaining the shield in operative position on the skillet. Both corners of each wing are preferably rounded, as indicated at 24 and 25, for the lower and upper corners, respectively, so that the shield presents no sharp corners or angles which could possibly injure a person using it.

The body portion of the shield can be slightly bent, as well as the tabs 20 and 21, to increase or reduce the curvature of the body portion by an amount sufficient to cause the shield to fit skillets of several different sizes and once the shield has been shaped to properly fit a particular skillet or frying pan, it can be mounted on the skillet or frying pan by merely placing it thereon and, because of the construction and arrangement of the tabs and the wings of the shield, will not accidentally fall off the skillet during use. Obviously, the shield may be placed at any desired

angular position around the rim of the skillet and, when removed from the skillet, it is extremely easy to clean and requires little space for storage.

The invention may be embodied in other specific forms without departing from the spirit or essential characteristics thereof. The present embodiment is, therefore, to be considered in all respects as illustrative and not restrictive, the scope of the invention being indicated by the appended claim rather than by the foregoing description, and all changes which come within the meaning and range of equivalency of the claim are, therefore, intended to be embraced therein.

What is claimed is:

A skillet grease shield comprising a one-piece body of sheet metal arcuately curved in one direction on a radius of curvature slightly less than the radius of curvature of the rim of a skillet on which the shield is to be used, said body having a length sufficient to include an angle of approximately 180-degrees and having spaced-apart means along one edge for mounting it on the rim of a skillet so that it is disposed almost entirely within the skillet rim, said one edge being arcuately curved so that said shield will incline upwardly and inwardly from a skillet rim on which it is mounted, and said means for mounting said shield on the rim of a skillet comprising a pair of elongated tabs of U-shaped cross-section extending from the convex side of said shield at said one edge of the latter and disposed at opposite sides of the

mid-length location of said one edge, and outwardly-deflected wings disposed one at each end of said body and recessed at their ends adjacent said one edge of said body to receive a skillet rim.
